UNITED STATES PATENT OFFICE.

HIRAM H. SPONENBURG, OF WADSWORTH, ILLINOIS, ASSIGNOR OF ONE-HALF TO EDWARD LAAS, OF OTTUMWA, IOWA.

RAILWAY-RAIL STAY.

SPECIFICATION forming part of Letters Patent No. 783,552, dated February 28, 1905.

Application filed December 12, 1904. Serial No. 236,447.

To all whom it may concern:

Be it known that I, HIRAM H. SPONENBURG, of Wadsworth, in the county of Lake, in the State of Illinois, have invented new and useful 5 Improvements in Railway-Rail Stays, of which the following, taken in connection with the accompanying drawings, is a full, clear, and exact description.

This invention relates to the class of devices 10 which are clamped to railway-rails and abut against the cross-tie for the purpose of preventing longitudinal movement of the rails, which movement is due to the continual travel of trains over the railway in one direction and 15 tends to throw the rails out of alignment.

The present invention has special reference 20 to the style of rail-stay which is composed of a bar extending across the bottom of the rail and abutting against the side of the cross-tie 25 and provided at one end with a rigid flange-gripping jaw and a clamping-jaw supported movably on the bar and forced onto the rail by a screw or bolt.

The object of the present invention is to 25 produce a rail-stay of the above style which shall be very efficient for the purpose stated and simple, strong, and durable and at the same time inexpensive to manufacture.

To this end the invention consists in the 30 novel construction and arrangement of the component parts of the rail-stay hereinafter fully described, and set forth in the claims.

In the accompanying drawings, Figure 1 is a 35 side view of my improved rail-stay applied to the rail. Fig. 2 is a plan view of the same. Fig. 3 is a transverse section on line X X in Fig. 2. Fig. 4 is a detail side view of the clamping-jaw with the rail shown in dotted lines. Fig. 5 is a detail inner face view of 40 said jaw. Fig. 6 is a side view of the rail-stay, showing a modification of my invention. Fig. 7 is a plan view of the modified form, and Fig. 8 is a transverse section on line Y Y in Fig. 7.

45 Similar letters of reference indicate corresponding parts.

A denotes the well-known track-rail, and B the usual cross-tie upon which the rail is supported.

The rail-stay embodying the present invention 50 comprises a metallic bar C, which extends across the bottom of the rail A and is formed with a depending flange a, by which it abuts against the side of the cross-tie B. The said bar is provided at one end with a rigid hook-shaped jaw a', preferably formed integral therewith and gripping one of the rail-flanges b, and on the opposite end of the bar is formed an upwardly-projecting lug c, provided with an aperture d. When I use the form of stay 60 shown in Figs. 1 and 2 of the drawings, I provide the said aperture with a screw-thread. The said bar C is formed on its top with a pair of guides or flanges e e, extending from the said lug c to a point a short distance beyond the edge of the adjacent flange b of the rail, and on the said guides are provided ribs f f, extending from their inner ends part way 65 their lengths, as clearly shown in Fig. 2.

D denotes a clamping-jaw mounted on top 70 of the bar and longitudinally adjustable between the guides e e. This jaw is formed on its bottom with a pair of oppositely-disposed tongues g g, engaging the aforesaid ribs f f of the guides, and is thereby sustained in its 75 position to grip the other flange b of the rail. The face of the jaw which engages the edge of the flange is preferably serrated, so as to obtain a more secure hold on the rail.

Through the aperture d of the aforesaid 80 lug c passes a horizontal screw h, which bears with its inner end against back of the jaw D and forces the same to its clamping position. The outer end of the said screw h is provided with a head i, by which to turn the same. 85 When the form of a stay shown in Figs. 6 and 7 of the drawings is used, the lug is provided with a plain aperture d, through which the screw h freely passes. In this case the screw engages a nut a', which is formed separate from the bar and is seated in a V-shaped recess b' in the top of the bar to prevent the same from shifting and turning when the screw is operated.

It will be observed that by extending the 95 aforesaid ribs f f only part way the length of the guides e e the clamping-jaw D can be readily removed from or applied to the bar.

It will also be seen that the clamping-jaw can be easily and conveniently tightened when required.

What I claim is—

- 5 1. A rail-stay comprising a bar extending across the bottom of the rail and engaging the cross-tie, a rigid jaw on one end of the bar engaging one of the rail-flanges, an adjustable jaw mounted on the bar and engaging the opposite rail-flange, and means passing through the bar and forcing the latter jaw onto the rail as set forth.
- 15 2. A rail-stay comprising a bar extending across the bottom of the rail and abutting against the cross-tie and formed on one end with a jaw engaging one of the rail-flanges and at the opposite end with longitudinal guides, a jaw supported on the bar adjustably between said guides and engaging the other rail-flange, and means movable lengthwise the bar for forcing the latter jaw onto the rail as set forth.
- 25 3. A rail-stay comprising a bar extending across the bottom of the rail and abutting against the cross-tie, a hook-shaped jaw formed on one end of the bar and engaging one of the rail-flanges, longitudinal guides formed on top of the bar at its opposite end, a clamping-jaw disposed adjustably between said guides and engaging the other rail-flange, and means passing through the bar and forcing the latter jaw to its clamping position as set forth.
- 35 4. A rail-stay comprising a bar extending across the bottom of the rail and formed with an abutment engaging the side of the cross-tie and formed at one end with a jaw gripping one of the rail-flanges, a clamping-jaw mounted adjustably on the opposite end portion of the bar and engaging the other rail-flange, and a screw extending lengthwise the bar and operative for forcing the latter jaw to its clamping position as set forth.
- 45 5. A rail-stay comprising a bar extending across the bottom of the rail and abutting against the cross-tie and provided at one end with a rigid jaw gripping one of the rail-flanges and provided at its opposite end with longitudinal guides, a clamping-jaw disposed adjustably between said guides and engaging the other rail-flange, and a horizontally-disposed screw supported on said bar and forcing the latter jaw to its clamping position as set forth.
- 55 6. A rail-stay comprising a bar extending across the bottom of the rail and abutting against the cross-tie and provided on one end with a rigid jaw gripping one of the rail-flanges, a clamping-jaw mounted longitudinally adjustable on the opposite end portion of the bar and engaging the other rail-flange and removable vertically therefrom, and means operative for forcing the latter jaw to its clamping position as set forth.
- 65 7. A rail-stay comprising a bar extending

across the bottom of the rail and abutting against the cross-tie and formed on one end with a jaw engaging one side of the rail, an adjustable clamping-jaw mounted on the bar and engaging the opposite side of the rail, and a horizontally-disposed screw supported on the bar and bearing on the back of the latter jaw and forcing the same to its clamping position as set forth.

70 8. A rail-stay comprising a bar extending across the bottom of the rail and abutting against the cross-tie and formed at one end with a jaw gripping one of the rail-flanges and formed at its opposite end with an apertured lug, a clamping-jaw mounted longitudinally adjustable on the bar, and engaging the other rail-flange and a screw passing through said lug and operative for forcing the latter jaw to its clamping position as set forth.

75 9. A rail-stay comprising a bar extending across the bottom of the rail and abutting against the cross-tie, and formed at one end with a jaw gripping one of the rail-flanges, and formed at its opposite end with an apertured lug and longitudinal guides back of the lug, a clamping-jaw mounted on top of the bar longitudinally adjustable between said guides, and a horizontal screw passing through the said lug and bearing on the back of the latter jaw and forcing the same to its clamp- 85 90 95 position as set forth.

10. A rail-stay comprising a bar extending across the bottom of the rail and abutting against the cross-tie and formed at one end with a jaw gripping one of the rail-flanges and formed at its opposite end portion with a pair of longitudinal guides disposed on top thereof and provided with ribs extending part way their lengths, a clamping-jaw disposed longitudinally adjustable between said guides and engaging the other rail-flange and formed at its opposite sides with tongues engaging said ribs, and a screw operative for forcing the latter jaw to its clamping position as set forth.

100 11. A rail-stay comprising a bar extending across the bottom of the rail and abutting against the cross-tie and formed at one end with a jaw gripping one of the rail-flanges and formed at its opposite end portion with a pair of longitudinal guides on the top thereof, said guides being provided with ribs extending part way their lengths, a clamping-jaw disposed longitudinally movable between said guides and engaging the other rail-flange and formed with tongues engaging said ribs, and a horizontally-disposed screw passing through the bar and bearing on the back of the latter jaw and forcing the same to its clamping position as set forth.

105 12. A rail-stay comprising a bar extending across the bottom of the rail and abutting against the cross-tie, said bar being formed at one end with a hook-shaped jaw gripping one of the rail-flanges and formed at its op- 110 115 120 125

posite end with an upwardly-projecting apertured lug, and longitudinal guides on top of the bar extending from the lug and provided with ribs extending from their inner ends 5 part way toward said lug, a clamping-jaw disposed longitudinally movable between the guides and engaging the other rail-flange and formed with tongues engaging the said ribs, and a horizontal screw passing through the 10 aforesaid lug and forcing the latter jaw to its clamping position as set forth.

13. A rail-stay comprising a bar extending across the bottom of the rail and abutting against the cross-tie, said bar being provided 15 at one end with a rigid jaw gripping one of the rail-flanges, a clamping-jaw sustained adjustably on the bar and engaging the other rail-flange, a separately-formed nut locked to the bar, and a screw passing freely through 20 the bar and engaging the nut and operative for forcing the latter to its clamping position as set forth.

14. A rail-stay comprising a bar extending across the bottom of the rail and formed at 25 one end with a jaw gripping one of the rail-flanges and at its opposite end with an upwardly-projecting lug provided with a plain

aperture, and a recess in the top of the bar, a clamping-jaw sustained longitudinally adjustable on the bar and engaging the other 30 rail-flange, a nut seated in said recess, and a screw passing freely through the lug and engaging said nut and bearing on the back of the latter jaw for forcing the same to its clamping position as set forth.

15. A rail-stay comprising a bar extending across the bottom of the rail and formed at one end with a jaw gripping one of the rail-flanges and at its opposite end with a lug provided with a plain aperture, a pair of longitudinal guides formed on the top of the bar, a recess in the top thereof and disposed between the guides, a clamping-jaw movable longitudinally on the guides and engaging the other rail-flange, a nut seated immovable in 45 said recess, and a horizontal headed screw passing freely through the aforesaid lug and engaging said nut and bearing on the back of the latter jaw for forcing the same to its clamping position as set forth.
